UNITED STATES PATENT OFFICE

2,178,430

FLASH LAMP

Richard S. Mackie, Cleveland Heights, Ohio, assignor to General Electric Company, a corporation of New York

Application March 30, 1937, Serial No. 133,875

7 Claims. (Cl. 67—31)

My invention relates to flash lamps and more particularly to that type of flash lamp used for photographic purposes which usually comprises a sealed transparent bulb in which is enclosed a sealed transparent bulb in which is enclosed a 5 readily combustible material, such as metal foil or wire, together with a substance, usually a gas filling, which, upon ignition, enters into a reaction with the combustible material with the resulting emission of actinic light.

10 To initiate the actinic reaction, it is necessary to provide some form of ignition means therefor. The type of ignition means customarily employed for such purpose comprises a resistance element or filament embedded in a bead of ignition paste and supported within the bulb in close proximity to the combustible material by a conventional mount structure. The ignition paste generally used is extremely sensitive, and when the electrical circuit through the filament 15 is energized, the heated filament promptly ignites the bead of ignition paste which in turn ignites the combustible material, thus initiating the actinic reaction.

As a safeguard against explosion of the glass bulb when a lamp of this type is flashed, it is customary to test the same for the presence of air. One desirable method of conducting such a test, known as a coil test, consists in the use of high frequency equipment employing glow tubes. 20 It has been found, however, that such a method of testing results in the loss of a great number of flash lamps through the premature flashing of the same, termed flash-outs, which is caused by the ignition of the extremely sensitive bead of ignition paste by the high frequency of the test equipment. In addition, accidental smashing or breaking of a flash lamp may ignite the bead of ignition paste so that the lamp catches fire. Furthermore, the bead of ignition paste is very 25 fragile, and frequently cracks or breaks off during shipment or other handling of the lamp. I have accordingly devised a novel form of ignition means or primer bead for flash lamps which prevents the premature flashing of the same, eliminates the danger of such lamps catching fire when smashed or broken, and possesses increased mechanical strength and resistance to cracking and breaking off.

One object of my invention is to provide an improved flash lamp which will not flash prematurely when subjected to various external phenomena, such as sparks induced by high frequency, corona, or the like.

Another object of my invention is to provide an improved flash lamp which will not catch fire

and burn when accidentally smashed or broken.

Still another object of my invention is the provision of a novel form of ignition means for flash lamps which will not ignite when subjected to various external phenomena, such as sparks induced by high frequency, corona, and the like, or when the lamp is smashed or broken.

A further object of my invention is the provision of a coating of lacquer or other similar non-conducting material on the bead of ignition 10 paste of a flash lamp, which coating will exclude such paste from various external phenomena normally tending to ignite it.

A still further object of my invention is the provision of a coating of non-conductive material on the bead of ignition paste of a flash lamp, which coating preferably consists of a lacquer composed of a resin solution, a nitro-cellulose lacquer, and a plasticizer.

Another object of my invention is the provision of a coating of thermoplastic material on the primer bead of a flash lamp which coating will cause metal foil or wire of the lamp to adhere to the bead during the sealing in operation.

A further object of my invention is the provision of a coating on the primer bead of a flash lamp which will add mechanical strength to the bead and prevent it from cracking and breaking off.

Other objects and advantages of my invention 30 will appear from the following description of species thereof and from the accompanying drawing, in which:

Fig. 1 is an elevation of a flash lamp comprising my invention in which the ignition means 35 comprises a bead of ignition paste enclosing the filament and coated with a layer of thermoplastic non-conductive material, and Fig. 2 is an enlarged fragmentary sectional view of a portion of a bead of ignition paste coated in accordance with my invention.

Referring to Fig. 1, the lamp comprises a vitreous bulb 10 containing a small filament 11, the ends of which are connected to lead-in wires 12, 12 which extend through a stem 13 to the 45 base 14. The filament 11 is embedded in a fulminating substance 15 to thereby form the ignition means for the lamp. A disc 16, preferably of asbestos, is mounted on the stem 13 to shield the base end of the lamp from the heat of combustion. The bulb 10 is loosely filled with combustible material 17, consisting of metal foil or wire, usually of aluminum.

The fulminating substances or primer bead 15 customarily employed in flash lamps of the type

described above is composed of an extremely sensitive metal powder 18, such as zirconium metal, together with an oxidizing agent, such as lead peroxide, mixed with a suitable binder, such as lacquer. When a bead of this paste dries, the metal powder particles at the surface protrude therefrom, and under the microscope have the appearance of fuzz. It is this fuzz that causes the bead of ignition paste to flash when a slight spark or even corona strikes the same. Similarly, the friction apt to be exerted on such fuzz when a flash lamp is accidentally smashed or broken might cause the bead of paste to flash, with the attendant danger of fire. By covering this fuzz or roughened surface with a coating of a suitable non-conductive substance 19, as shown in Fig. 2, the metal powder 18 is thereby excluded from the action of all external phenomena thereon tending to ignite the same, such as sparks induced by high frequency, or corona, friction, and the like. In this manner, the premature flashing of the bead of ignition paste 18, and of the flash lamp itself, during test or when broken, is prevented. In addition, the coating 19 definitely adds a considerable amount of mechanical strength to the fragile bead of ignition paste, thereby reducing the danger of the bead cracking and breaking off during shipment and other handling of the lamp.

30 The coating material 19 may consist of a mixture of a synthetic or natural resin solution with or without nitrocellulose lacquer and with or without a suitable plasticizer, dissolved in suitable solvents. The synthetic resin solution I prefer to use is that commercially known as Glyptal varnish, but the resin contained therein may be any other resin having thermoplastic properties. The nitrocellulose lacquer may consist of nitrocellulose dissolved in a suitable solvent or solvents, such as acetone, while the plasticizer may be dibutylphthalate, tricresylphosphate, or some other similar substance. The above mixture of a resin solution, nitrocellulose lacquer and a plasticizer is diluted with a suitable thinner or diluent, preferably that known as Ault and Viborg thinner H8349. The coating material may be applied to the fulminating substance or primer bead 15 by simply dipping such bead in the coating material and allowing the latter to dry thereon. During this drying process, the aforementioned thinner or diluent evaporates, leaving a coating of solid material on the fulminating substance consisting of the mixture of a resin solution, nitrocellulose lacquer and a plasticizer referred to above.

55 The synthetic resin preferably employed in the coating material 19, and commercially known as Glyptal, possesses the property of thermoplasticity; or, in other words, it becomes plastic upon the application of heat thereto. This resin is present in sufficient quantity in the coating material 19 to impart this property of thermoplasticity to the coating material itself, so that the heat attending the sealing of the mount in the bulb renders such coating material plastic. Any portion of the metal foil or wire 17 within the lamp coming into contact with the coating material while the same is in such a plastic state will permanently adhere to such coating material and accordingly to the primer bead, thus insuring positive and instantaneous ignition of the metal foil or wire upon the ignition of the primer bead.

Although the preferred form of the invention is shown and described herein, it is to be understood that modifications may be made therein, such as the use of coatings of a composition other than those mentioned above, without departing from the spirit and scope of the invention as described herein and as set forth in the appended claims.

What I claim as new and desire to secure by Letters Patent of the United States is:

1. A flash lamp comprising a sealed container, a quantity of combustible material within said container, and means for igniting said combustible material, said means including a bead of highly sensitive fulminating substance comprising readily ignitable metallic powder and coated with a layer of material comprising a mixture of a thermoplastic resin solution and a nitrocellulose lacquer. 10
2. A flash lamp comprising a sealed container, a quantity of combustible material within said container, and means for igniting said combustible material, said means including a bead of highly sensitive fulminating substance comprising readily ignitable metallic powder and coated with a layer of material comprising a mixture of a thermoplastic resin solution and a plasticizer. 15
3. A flash lamp comprising a sealed container, a quantity of combustible material within said container, and means for igniting said combustible material, said means including a bead of highly sensitive fulminating substance comprising readily ignitable metallic powder and coated with a layer of material comprising a mixture of a thermoplastic resin solution, a nitrocellulose lacquer, and a plasticizer. 20
4. A flash lamp comprising a sealed container, a quantity of combustible material within said container, and means for igniting said combustible material, said means including a bead of highly sensitive fulminating substance comprising readily ignitable metallic powder and coated with a layer of thermoplastic lacquer. 25
5. A flash lamp comprising a sealed container, a quantity of combustible material within said container, and means for igniting said combustible material, said means comprising an electrical translation element embedded in a bead of highly sensitive fulminating substance comprising readily ignitable metallic powder, said bead being coated with a layer of thermoplastic lacquer. 30
6. A flash lamp comprising a sealed container, a quantity of combustible material within said container, and means including a bead of highly sensitive fulminating substance comprising readily ignitable metallic powder for igniting said combustible material, a portion of said combustible material being securely attached to said bead of fulminating substance by a thermoplastic lacquer. 35
7. A flash lamp comprising a sealed container, a quantity of combustible material within said container, and means for igniting said combustible material including a bead of highly sensitive fulminating substance comprising readily ignitable metallic powder, said bead having thereon a protective coating of thermoplastic resinous lacquer of sufficient thickness to prevent ignition of said bead upon breakage of the said container. 40
